UNITED STATES PATENT OFFICE.

EINAR J. BRING, OF SCHENECTADY, NEW YORK, ASSIGNOR TO GENERAL ELECTRIC COMPANY,
A CORPORATION OF NEW YORK.

LUBRICATING DEVICE.

No. 895,954.

Specification of Letters Patent.

Patented Aug. 11, 1908.

Application filed April 8, 1904. Serial No. 202,132.

To all whom it may concern:

Be it known that I, EINAR J. BRING, a subject of the King of Norway and Sweden, residing at Schenectady, county of Schenectady, State of New York, have invented certain new and useful Improvements in Lubricating Devices, of which the following is a specification.

The present invention relates to devices 10 for lubricating, and in its broadest aspect is capable of use in many relations. It is herein shown and described in connection with a double-cylinder air-compressor.

The invention comprises a novel oil pump 15 having a piston located in an oil basin, and a cylinder into and out of which the piston is adapted to pass as the pump is operated, so that at each reciprocation, a definite amount of oil is collected in the cylinder and forced 20 from it through suitable distributing ducts to the parts to be lubricated.

The character of the invention will be best understood from the following detailed description taken in connection with the accompanying drawings, and the various features and combinations which I regard as my invention will be particularly pointed out in the appended claims.

In the drawings, Figure 1 is a view of a 30 portion of an air-compressor, showing the compressing pistons in elevation and a lubricating device constructed in accordance with my invention attached thereto; and Fig. 2 is an end view of such device and a portion of 35 the compressing pistons.

In both of these views like characters refer to like parts.

The air-compressor illustrated is substantially the same as that disclosed in the application of Asa F. Batchelder, Serial No. 74,244, 40 filed Sept. 3, 1901, but differs therefrom in comprising certain improvements in piston construction which are herein shown but not claimed since the same are to be presented in a separate application. For the purposes of 45 this case it is sufficient to state that the compressing pistons 10 and 11 are arranged in line and as they reciprocate in their cylinders formed in the casing 12 draw in air upon 50 one stroke and compress it on the other. Each of the pistons 10, 11 is composed of a single casting which includes suitable spring cases 13 and 14 in which are located springs 55 which are arranged to draw the pistons toward each other. A driving crank-shaft

16 is located between the pistons 10 and 11. Motion is transmitted from the crank-shaft through pitmen 17, 18 which bear at their opposite ends against the crank-pin 19 and suitable wrist-pins 20 and 21 carried by the 60 pistons 10 and 11 respectively. Secured to the lower part of the casing 12 is an oil basin 22 which is provided with an open top 23.

The oil device comprises a casting 24 which is detachably secured by bolts 25 to the casting of the piston 10. The casting 24 is provided at its lower end with a horizontally-disposed cylinder 26 which extends into the oil in the basin 22. A fixed piston 28 located within the basin 22 is adapted to pass into 70 and out of the bore 27 of the cylinder 26 as the pistons of the compressor reciprocate. A slight clearance is provided between the piston 28 and the interior of the cylinder 26, so that these parts never come into wearing 75 engagement but are always separated by a film of oil. Consequently the parts of the pump are practically indestructible. The chamber 27 of the cylinder communicates with suitable ducts 29 which lead to the parts 80 to be lubricated. These ducts are formed in part by holes drilled in the casting 24 and in part by tubes connecting said holes. As clearly illustrated, they lead to the delivery points 30, 31 and 32 at the upper side of the 85 wrist-pins 20 and 21 and the crank-pin 19.

The amount of oil delivered to the bearings depends upon the clearance between the cylinder 26 and its piston 28 and the relative capacities of the chamber 27 and the ducts 90 29. The capacity of the chamber 27 should exceed that of the ducts by an amount sufficient for the lubrication of the bearings. This amount may be varied by varying the longitudinal position of the piston 28 by 95 screwing it in or out of the casing.

The operation of the device is as follows: The cylinder 26 reciprocates with the compression pistons 10 and 11 and at each to and fro movement supplies a definite amount of 100 oil to the bearings of the compressor. In its movement in one direction, the cylinder 26 passes beyond the piston 28 and oil from the basin 22 flows into the chamber 27. Upon its return movement, the cylinder forces the 105 collected oil from said chamber up through the distributing ducts 29 and by reason of the relative capacities of the chamber 27 and the ducts 29 a small amount of oil is supplied to the bearings. As the cylinder 26 is drawn 110

- from the piston 28 any oil that remains in the ducts 29 is drawn back into the cylinder and mingles with the new supply of oil from the basin admitted when the cylinder passes 5 clear of the piston. The oil that is supplied to the bearings may readily drain off into the chamber beneath the compressor pistons and thence into the oil basin to be used over again.
- 10 From the above it will be seen that I have devised a valveless oil pump which is simple and durable in construction and positive in its action. It will also be apparent to those skilled in the art that modifications and alterations 15 may be made in the device which I have shown without departing from the spirit and scope of my invention. I therefore do not wish to be limited to the specific matter shown but aim to cover by the terms 20 of the appended claims all such alterations and modifications.

What I claim as new and desire to secure by Letters Patent of the United States, is:

1. An oil pump comprising an oil basin, a 25 cylinder open at one end and having a duct leading from near the other end and arranged for reciprocation in said basin, a piston located in said basin and arranged to enter said cylinder as the latter is reciprocated, 30 and means for adjusting the extent to which the piston enters the cylinder.
2. An oil pump comprising an oil basin, a cylinder open at one end having a duct leading from near the other end and arranged for 35 reciprocation in said basin, a piston located in said basin and arranged to enter said cylinder as the latter reciprocates, and means for adjusting the piston relatively to the cylinder.

3. The combination of an oil basin, a reciprocating piston, an operating pitman therefor, a pump extending into said basin and operated by said piston, and distributing oil ducts leading from said pump to the bearing surfaces of said piston and pitman. 40

4. The combination of an oil basin, a piston fixed therein, a reciprocating member, and a casting detachably secured to said member and provided with oil distributing ducts and a cylindrical chamber communicating 50 with said ducts into which the fixed piston is adapted to pass when said member reciprocates.

5. The combination with an oil basin, of an oil pump comprising a piston fixed in said 55 basin, and a reciprocating cylinder into which said piston is adapted to pass as the cylinder reciprocates, said cylinder having a movement beyond the end of the piston as it reciprocates.

6. The combination with an oil basin, of an oil pump comprising a piston fixed in said 60 basin, and a reciprocating cylinder into which said piston is adapted to pass as the cylinder reciprocates, said cylinder having a 65 movement beyond the end of the piston as it reciprocates and there being a clearance between it and the piston whereby part of the oil which flows into the cylinder at each stroke is allowed to escape back into the 70 basin.

In witness whereof I have hereunto set my hand this 6th day of April, 1904.

EINAR J. BRING.
